UNITED STATES PATENT OFFICE.

DANA M. STEPHENS, OF CHARLOTTE, NORTH CAROLINA, ASSIGNOR TO JANET GARMENT COMPANY, OF CHARLOTTE, NORTH CAROLINA, A CORPORATION.

METHOD OF PRODUCING FULLNESS IN THE SEAT OF UNDERWEAR.

Application filed January 9, 1922. Serial No. 528,106.

To all whom it may concern:

Be it known that I, DANA M. STEPHENS, a citizen of the United States, residing at Charlotte, in the county of Mecklenburg 5 and State of North Carolina, have invented a new and useful Method of Producing Fullness in the Seat of Underwear.

This invention relates to certain new and useful improvements in nethergarments and 10 pertains more especially to garments of the bifurcated type, for feminine wear, whether of the union, or combination, or other type of garments.

The primary object of the invention is to 15 provide a garment which is constructed to afford fullness in the seat for the purpose of increasing the life of the garment and adding comfort to the wearer.

Still further the invention aims to provide 20 a construction which adds fullness to the seat without causing the garment to droop between the legs, and which relieves the strain on the buttons and buttonholes when the wearer is in either a sitting or stooping 25 position.

In the drawings:—

Figure 1, is a rear elevation of the invention:

Figure 2, is an enlarged section on line 30 2—2 of Figure 1, and

Figures 3 and 4 are views similar to Figure 2 of modifications of the invention.

In proceeding in accordance with the present invention, each leg 1 of the garment 35 on the rear side thereof, is formed with a plait 2. The plait extend from points near the lower ends of the legs upwardly toward the waist line or belt 3 and terminate at points adjacent to the beginning of the seat 40 of the garment, and are secured by lines of stitching 4, the latter located adjacent to the lower ends of the plaits. The two plaits are

disposed equi-distantly from the back seam 5 of the garment and due to stitching 4, it will be seen that effective anchorages are 45 afforded for the plaits and the latter are permanently maintained. Tucks, as shown at 6 in Figure 3, may be employed in lieu of the plaits, or gathering as depicted in Figure 4, may be employed, if desired, either 50 affording the desired fullness. The pleats, tucks, or gathering also afford lines of reinforcement of strengthening, relieving the buttons and buttonholes of strain when the wearer is in either a sitting or stooping 55 position. Since the folds, plaits, tucks or gathering are secured to the legs of the garment, only at the ends thereof, it will be apparent that the parts between such ends can freely expand to thus impart the desired 60 fullness to the seat portion of the garment, affording greater comfort to the wearer and increased life to the garment. In Figure 4, the gathering is secured at its lower end by a strip of cloth 8. 65

What is claimed is:

A bifurcated nether garment having a belt, integral seat and leg forming portions, which latter at the backs thereof are stitched throughout the extent of their upper ends 70 to the belt and are connected by a vertical back seam, folded portions in the legs extending upwardly for a substantial distance from the lower ends of the legs and located on opposite sides of the back seam, and 75 stitching affording anchors for the lower ends of the folded portions and terminating just above the level of the crotch, the folded portions being formed to effect increased fullness of the seat upon the wearer assuming a sitting or stooping position and extending into the seat. 80

DANA M. STEPHENS.
